(57) CLAIM

I claim the ornamental design for a bottle for water or other liquid, substantially as shown and described.

DESCRIPTION

FIG. 1 is a perspective view of a bottle for water or other liquid showing my new design;

FIG. 2 is a top plan view thereof;

FIG. 3 is a bottom view thereof;

FIG. 4 is a front side elevation view thereof;

FIG. 5 is a left side elevational view, the right side being a mirror image thereof; and,

FIG. 6 is a back side elevation view thereof.
